CLAIM

The ornamental design for a beverage dispensing cabinet, as shown and described.

DESCRIPTION

FIG. 1 is a top, front, left perspective view of a beverage dispensing cabinet showing our new design;

FIG. 2 is a perspective taken from the top, front and right side thereof;

FIG. 3 is a top, front, and right perspective view thereof;

FIG. 4 is a left side view thereof;

FIG. 5 is a right side view thereof;

FIG. 6 is a rear view thereof;

FIG. 7 is a top plan view thereof;

FIG. 8 is a top, front, left perspective view of a beverage dispensing cabinet showing a second embodiment of our new design;

FIG. 9 is a bottom plan view of both embodiments thereof. The side elevational views and rear elevational view of the second embodiment are identical to that of the first embodiment, the only difference being the lack of a protruding circular portion along the top.

1 Claim, 3 Drawing Sheets
